DESIGN FOR A COMBINED TWIN LIPSTICK CASE AND MIRROR COMPARTMENT OR THE LIKE

Elizabeth N. Graham, New York, N. Y.

Application September 11, 1947, Serial No. 141,314

Term of patent 14 years

(Cl. D86—10)

To all whom it may concern:

Be it known that I, Elizabeth N. Graham, a citizen of the United States of America, residing in New York city, county of New York, and State of New York, have invented a new, original, and ornamental Design for a Combined Twin Lipstick Case and Mirror Compartment or the like, of which the following is a specification, reference being had to the accompanying drawing, forming part thereof, wherein:

I claim:

The ornamental design for a combined twin lipstick case and mirror compartment or the like, substantially as shown.

ELIZABETH N. GRAHAM.
